(57) **CLAIM**

The ornamental design for a buttstock, as shown and described.

DESCRIPTION

FIG. 1 is a rear perspective view of a buttstock in accordance with one embodiment of the present invention;

FIG. 2 is a left elevation view of the buttstock of FIG. 1;

FIG. 3 is a right elevation view of the buttstock of FIG. 1;

FIG. 4 is a front elevation view of the buttstock of FIG. 1;

FIG. 5 is a rear elevation view of the buttstock of FIG. 1;

FIG. 6 is a top plan view of the buttstock of FIG. 1;

FIG. 7 is a bottom plan view of the buttstock of FIG. 1;

FIG. 8 is a left perspective view of the buttstock of FIG. 1;

FIG. 9 is a left, front perspective view of the buttstock of FIG. 1;

FIG. 10 is a left elevation view of the buttstock of FIG. 1;

FIG. 11 is a rear perspective view of a buttstock in accordance with another embodiment of the present invention;

FIG. 12 is a left elevation view of the buttstock of FIG. 11;

FIG. 13 is a right elevation view of the buttstock of FIG. 11;

FIG. 14 is a front elevation view of the buttstock of FIG. 11;

FIG. 15 is a rear elevation view of the buttstock of FIG. 11;

FIG. 16 is a top plan view of the buttstock of FIG. 11;

FIG. 17 is a bottom plan view of the buttstock of FIG. 11;

FIG. 18 is a left perspective view of the buttstock of FIG. 11;

and,

FIG. 19 is a left elevation view of the buttstock of FIG. 11.

The broken lines shown herein are for illustrative purposes and form no part of the claimed design. For example, the alternating series of long and short dashed lines shown, for example, in FIGS. 1 and 15 encompasses an area that is not part of the claimed design.
